CLAIM

I claim the ornamental design for a lawn care vehicle, as shown and described.

DESCRIPTION

FIG. 1 is a front top perspective view of a lawn care vehicle showing our new design;

FIG. 2 is a rear top perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown represent the portions of the lawn care vehicle that form no part of the claimed design.
